UNITED STATES PATENT OFFICE.

CHARLES W. STEPHENSON, OF ELDORADO, ILLINOIS, ASSIGNOR OF ONE-HALF TO THOMAS S. WHITLEY, OF ELDORADO, ILLINOIS.

PIANO-HAMMER.

SPECIFICATION forming part of Letters Patent No. 777,444, dated December 13, 1904.

Application filed October 21, 1903. Serial No. 177,924. (No model.)

To all whom it may concern:

Be it known that I, CHARLES W. STEPHENSON, a citizen of the United States, residing at Eldorado, in the county of Saline and State 5 of Illinois, have invented new and useful Improvements in Piano-Hammers, of which the following is a specification.

My invention relates to new and useful improvements in hammers for pianos; and its 10 object is to provide an adjustable working face whereby worn surfaces can be readily removed from position above the strings and a smooth unworn surface presented thereto without detaching or repairing the felt constituting said working face.

As is well known, the hammers of a piano are soon worn by reason of their continual contact with the strings of the instrument, and in order to substantially repair the injury 20 thereto it is necessary either to provide new hammers or to pick the felt and remodel it. The first-mentioned remedy is extremely expensive, whereas the felt can never be picked out so as to be as effective as when originally 25 used.

One of the objects of my invention is to employ an adjustable felt which can be quickly moved, so as to present any portion of the surface thereof to the strings, and while said 30 portion is being used the previously-used face is automatically molded within the head of the hammer and prepared for further use.

With the above and other objects in view the invention consists in the novel construction and combination of parts hereinafter 35 more fully described and claimed and illustrated in the accompanying drawings, showing the preferred form of my invention, and in which—

Figure 1 is a side elevation of my improved hammer. Fig. 2 is a vertical longitudinal section therethrough. Fig. 3 is a horizontal section through the hammer. Fig. 4 is an elevation of a modified form of hammer, and 45 Fig. 5 is a view of said modified form of hammer removed from its socket and showing its condition subsequent to continual use.

Referring to the drawings by numerals of

reference, 1 denotes a head-piece having a socket 2, constructed of surrounding front, 50 rear, and side walls, the two opposite narrow walls of the socket being provided with extensions 3, projecting from and forming a part of the said side walls, whereby to detachably secure one portion of a circular hammer, which 55 comprises a core 4, formed of wood or other non-resilient material covered by an inclosing ring 5 of felt. The hammer is partially inclosed within the surrounding walls of the socket, and the extensions 3 serve to clamp 60 the hammer within the socket by means of the said extensions being bent against the periphery of said hammer, and said hammer is adjustable in the socket and in the extensions, it being turnable by the aid of the 65 hands of a person. After the working face of the hammer has been used for some time and becomes flat and worn it is merely necessary to turn the same within the socket 2, so as to bring said worn portion into contact 70 with the wall of the socket and present some other unworn portion of the ring to the strings. This operation can be quickly performed and obviates the necessity of employing special tools for repairing the rings. 75

The hammer above described can be used upon most of the strings of the piano; but for the higher strings I preferably use a hammer such as illustrated in Figs. 4 and 5. This form of device comprises a head 6, having a 80 socket 7 therein preferably substantially in the form of a half-oval, and within this socket is arranged a hammer formed of an oval core 8 of non-resilient material and a covering 9 of felt. This hammer presents a narrow 85 working edge to the strings, and when said edge becomes flattened, as illustrated in Fig. 5, the hammer can be withdrawn from the socket, reversed, and replaced in position. The subsequent use of the hammer will cause 90 the flattened portion thereof to be remolded and placed in condition for further use after the outer end thereof has been worn. This modified form of socket is also provided with integral ears 10 for overlapping and retaining 95 the hammer in position.

Having thus fully described my invention, what I therefore claim as new, and desire to secure by Letters Patent, is—

1. A piano-hammer holder comprising a one-part head-piece having a receptacle or socket formed by surrounding walls, the socket being provided with two opposite narrow walls and having extensions formed thereon at their terminal ends and projecting therefrom, said extensions being adjustable toward each other by means of the bending of the same, substantially as specified.

2. A piano-hammer comprising a head-piece having a receptacle or socket formed therein by means of surrounding walls, said socket being provided with two opposite narrow

walls having integral extensions projecting from the terminal ends of the same, a hammer partially inclosed within the receptacle and secured therein by bending the said extensions against the opposite sides of the periphery of the hammer, said extensions also serving to permit of said hammer being circumferentially adjusted within the receptacle, substantially as specified. 25

In testimony whereof I affix my signature in presence of two witnesses.

CHARLES W. STEPHENSON.
